UNITED STATES PATENT OFFICE

152,655

DESIGN FOR A FLORIST'S WIRE HOLDER

Hubert S. Rossell, Redwood City, Calif.

Application November 1, 1946, Serial No. 134,422

Term of patent 14 years

(Cl. D35—3)

To the Commissioner of Patents:

Be it known that I, Hubert S. Rossell, a citizen of the United States, residing in the county of San Mateo, State of California, have invented a certain new, original, and ornamental Design for a Florist's Wire Holder, of which the following is a specification, reference being had to the accompanying drawing.

I claim:

The ornamental design for a florist's wire holder, substantially as shown.

HUBERT S. ROSELL.
